US00D940495S

(12) **United States Design Patent** (10) Patent No.: **US D940,495 S**
(45) Date of Patent: ** Jan. 11, 2022

(54) **BAKEWARE**

- (71) Applicant: **ZHONGSHAN LIANSHENG INTELLIGENT TECHNOLOGY CO., LTD.**, Zhongshan (CN)
- (72) Inventors: **Juehao Huang**, Changsha (CN); **Houjun Huang**, Changsha (CN); **Bufo Li**, Changsha (CN); **Weiwu Man**, Changsha (CN)
- (73) Assignee: **ZHONGSHAN LIANSHENG INTELLIGENT TECHNOLOGY CO., LTD.**, Zhongshan (CN)

(**) Term: **15 Years**

(21) Appl. No.: **29/741,319**

(22) Filed: **Jul. 10, 2020**

(30) **Foreign Application Priority Data**

CLAIM

The ornamental design for a bakeware, as shown and described.

DESCRIPTION

FIG. 1 is a perspective view of the bakeware showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines illustrate portions of the bakeware that form no part of the claimed design.

1 Claim, 7 Drawing Sheets
